UNITED STATES PATENT OFFICE

HARRY P. PARCHMANN, OF CHICAGO, ILLINOIS, ASSIGNOR TO THEO. A. KOCHS COMPANY, OF CHICAGO, ILLINOIS, A CORPORATION OF ILLINOIS

DESIGN FOR A BARBER'S SIGN

Application filed October 16, 1929. Serial No. 33,044. Term of patent 7 years.

To all whom it may concern:

Be it known that I, HARRY P. PARCHMANN, a citizen of the United States, residing at Chicago, in the county of Cook and State of Illinois, have invented a new, original, and ornamental Design for a Barber's Sign, of which the following is a specification, reference being had to the accompanying drawing, forming part hereof, in which the figure showing my new design is a perspective view of a barber's sign having a central bracket portion indicated in dotted lines.

I claim:

The ornamental design for a barber's sign, as shown and described.

HARRY P. PARCHMANN.
